PRESS UNLOADER

Frederick W. Braun, Dearborn, Mich., assignor to
 General Motors Corporation, Detroit, Mich., a
 corporation of Delaware

Application February 13, 1940, Serial No. 318,778

3 Claims. (Cl. 113—50)

This invention relates to a press unloader and more particularly to a device for automatically unloading metal stampings from a press.

Presses for stamping or drawing sheet metal have proved dangerous instrumentalities and injuries to the operators of these presses occur from time to time. It is the object of this invention to increase the safety of the press operator and obviate some of the dangers inherent in press operation. This object has been achieved by a press unloader of very simple form which automatically unloads the stamping from the press without manual assistance from the operator.

In the drawings:

Fig. 1 is a side elevation showing in full lines the operative position of the unloader when the dies are open and in the dotted lines the position of the unloader when the press is closed.

Fig. 2 is a front elevation of the press and press unloader showing in the full lines the position of the unloader when the press is open and showing in the dotted lines the position of the parts of the unloader when the press is closed.

Fig. 3 is a plan view of the press and unloading device.

Fig. 4 is a side elevation of a modified form of unloader showing in the full lines the operative position of the unloader when the dies are opened and showing in the dotted lines the position of the unloader when the press is closed.

Referring more particularly to the drawings there is shown a press having a lower composite die comprising stationary member 1 in which is yieldably mounted on springs 50 the die member 51 and an upper reciprocating die member 2. The particular stamping that the dies are designed to form is the center pillar 3 of an automobile body.

Preparatory to automatically unloading the stamping from the press it is essential that the center pillar stamping 3 be elevated with the vertically reciprocating die 2 which is commonly called the male die or punch. To this end the die 2 is provided with two pairs of fingers 4 which are fixed on vertical shafts 5 journaled in the die member 2. A crank 6 is fixed to the upper end of each shaft 5. The cranks 6 are pivotally connected to the sliding bars 7 as at 11. The bars 7 are slidable in grooves 8 in the upper face of die 2 and retained therein by plates 9. The bars 7 are connected at their outer end by the cross bar 10. The lower die is recessed as at 12 to receive fingers 4 when the press is closed and to permit the fingers 4 to swing inwardly beneath the pillar stamping 3.

For swinging the fingers 4 inwardly against the stamping 3 and for swinging them outwardly to release the stamping 3, there is provided a lever 13 pivotally mounted on bracket 14 which is fixed on die 2. The upper end of lever 13 is pivotally connected as at 15 to cross bar 10. The lower end of the lever 13 is preferably provided with a roller 16 arranged to roll along the cam member 17 which is fixed to the lower stationary die 1. The cam member 17 is provided at the top and bottom with the inclined cam surfaces 18 and 19 respectively. The fingers 4 are normally held in released position by the compression spring 20 positioned between the lever 13 and the face of the upper die 2.

As shown in the dotted lines Fig. 2, the press is closed and the metal sheet has been formed into the center pillar 3. At this time roller 16 is below cam surface 19 and the fingers 4 are in released position as shown in Fig. 3. As the upper die 2 rises, springs 50 raise die 51 a short distance of about one and one-half inches and roller 16 rides upwardly and outwardly along cam surface 19, thus through lever 13 shifting slides 7 to the left, Figs. 2 and 3, and rotating fingers 4 about shafts 5 so that they clamp stamping 3 against die 2. Hence, as the die 2 moves upwardly, stamping 3 is withdrawn from the lower die member 1 and carried upwardly by fingers 4, see Fig. 2. The fingers 4 continue to clamp stamping 3 against die 2 as long as the roller 16 rolls along the straightaway surface 21 of cam 17. As roller 16 reaches cam surface 18, the lever 13 is swung clockwise by spring 20 thus sliding slides 7 to the right, Figs. 2 and 3. As slides 7 are shifted to the right, Fig. 3, fingers 4 are withdrawn from clamping contact against the stamping 3 and it falls downwardly upon the press unloader platform 30 which will now be described.

The press unloader platform 30 comprises a plate which is supported at each end by arms 31. Arms 31 are welded or otherwise fixed to links 32. Each link 32 has one end pivotally connected to the die 2, as at 33, and the other end pivotally connected to link 34, as at 35. The lower end of link 34 is pivotally connected as at 36 to the lower die 1.

The operation of the device is as follows: As shown in the dotted lines, Figs. 1 and 2, the press is closed, the pillar 3 has been formed and the press unloader 30 is swung outwardly to an operative position because the links 32 and 34 at this time are jackknifed or collapsed. As the die 2 rises, fingers 4 swing inwardly against the stamping 3, raising the same with the die 2 as

above described. Upward movement of the die 2 causes the links 32 and 34 to straighten, thereby swinging the arm 31 and unloader platform 30 inwardly beneath the upper die 2, as shown in Fig. 1, where the unloader receives the stamping 3 as it is released by the outward swinging of fingers 4, as above described. The stamping slides by gravity down the platform 30 to discharge the same from the press.

As the die 2 moves downwardly, roller 16 slides downwardly and outwardly on cam 18 and along surface 21 and then down cam 19 which through lever 13 and slides 7 retract fingers 4. Roller 16 reaches cam 19 about the time that die 2 first contacts the raised lower die portion 51. As soon as the stamping operation on pillar 3 is complete, the die 2 rises and the cycle is repeated as above described.

In Fig. 4 there is shown a modified form of unloader platform. In this form the unloader platform 40 is adjustably secured on arm 41 pivotally mounted as at 42 on a member 43 fixed to the stationary frame 44 of the press. An arm 45 is fixed to the arm 41. Arm 45 is pivotally connected as at 46 to link 47 which is pivotally connected as at 48 to the upper vertically reciprocating die 49.

In the full line showing of Fig. 4 the press is open and the upper die 49 is raised so that the platform 40 is positioned beneath the upper die 49 to receive the stamping 3 as it is discharged from the upper die by the means and in the manner above described. After the stamping 3 has been deposited on the platform 40, the upper die 49 again descends whereby link 47 swings arm 41 and platform 40 to the dotted line position, Fig. 4, causing the stamping 3 to slide off of the platform 40.

The term "die" is used broadly herein to include not only the member which actually forms the metal but also the support for such member.

I claim:

1. In a press comprising a lower stationary die and an upper die member movable downwardly toward and upwardly away from the lower die, an unloader for removing the work from the

press in the form of a platform, a pair of substantially vertical normally disaligned links pivotally connected to each other and to the said upper and lower die members, said platform being rigidly fixed to said upper link whereby as the upper die moves upwardly from the lower die the links straighten and move the platform into work receiving position between the dies and as the upper die moves downwardly the links jackknife and withdraw the platform from between the dies.

2. In a press having cooperating dies relatively movable toward and away from each other, an unloader for removing the work from the press comprising a toggle having two legs, one end of the toggle being pivotally fastened to one of said dies and the other end of the toggle being pivotally fastened to the other die, said toggle being substantially but not completely straightened when said dies are in a position away from each other, a platform fastened to a leg of said toggle, said platform being positioned between the dies and extending outwardly and downwardly when the latter are in a position away from each other whereby the toggle is jack-knifed and the platform is withdrawn from between the dies when said dies move toward each other.

3. In a press having cooperating dies relatively movable toward and away from each other, an unloader for removing the work from the press comprising a toggle having two legs, one end of the toggle being pivotally fastened to one of said dies and the other end of the toggle being pivotally fastened to the other die, said toggle being substantially but not completely straightened when said dies are in a position away from each other, an arm fixed to one of said legs and extending between the dies when the dies are in a position away from each other, a platform mounted on the arm and being positioned between the dies when the latter are in a position away from each other whereby the toggle is jack-knifed and the said arm and platform are withdrawn from between the dies when the said dies move toward each other.

FREDERICK W. BRAUN.
